UNITED STATES PATENT OFFICE.

CHARLES M. YOUNG, OF LOCKPORT, NEW YORK.

HANGER FOR INSIDE BLINDS.

SPECIFICATION forming part of Letters Patent No. 253,469, dated February 7, 1882.

Application filed December 3, 1881. (No model.)

To all whom it may concern:

Be it known that I, CHARLES M. YOUNG, of the city of Lockport, in the county of Niagara and State of New York, have invented a new and Improved Mode of Hanging and Operating Venetian Window-Shades and Movable Screens; and I do hereby declare that the following is a full and exact description thereof, reference being had to the accompanying drawings and the letters of reference marked thereon, making a part of this specification.

My invention relates to an improvement in Venetian window-shades; and it consists in a bent plate or casting which is secured to each end of the upper slat of the blind, and which has a triangular opening or slot in it, so as to catch over a suitable support which is applied to the inner side of the window-frame, as will be more fully described hereinafter.

20 The object of my invention is to provide a hanger and attachments to Venetian window-shades or any other shades or screens which admit of their application, by means of which the said shades or screens can be suspended in such a manner that the slats, when closed and lapping upon each other, can be instantly and simultaneously reversed, so as to close and lap in the opposite direction, or made to open and lie horizontally for the admission of light 30 or air by a slight turning of the lower bar or slat, or by a gentle pull up or down, as the case requires, on either of the tapes which support and keep the slats in position.

I construct the hanger, Figure 1, of any suitable metal and attach the bed-plate A, with its open slot B, to the inferior face of the strong upper slat, E, as shown in Fig. 2, by means of screws or other suitable device, bringing the triangular portion C of the hanger at right

40 angles to the upper or superior face of the strong upper slat, in position for use.

Fig. 2 represents an end view of the hanger with its bed-plate A, open slot B, and triangular portion C attached to the upper slat of the blind.

45 Fig. 3 represents one side of the window-easing or screen-frame, with the pin or screw D in position to receive the hanger attached to the end of the strong upper slat, E, and a portion of said slat with hanger attached ready

for being placed in position, both ends of the slat being entirely similar, which operation can be performed either by holding the upper slat with its flat sides vertical and the open slots B of the hangers from the operator and passing them simultaneously upon the pins or screws D, or by holding the slat, with hangers attached, with its flat sides horizontal, and raising it high enough for the open slots B to receive the pins or screws D, and dropping the slat gently until the triangular portion of the hangers rests upon the pins or screws D, which completes the operation of hanging the shade or screen. The shade or screen can readily be removed by a reverse movement of the strong upper slat, to which the hangers are attached. When once in position and ready for use it is entirely secure from being detached from the pins or screws D by practical use.

55 I am aware that it is old to apply triangular-shaped frames to the top of the top slat, and which frames have openings through their centers, so as to catch over suitable hanging supports. My invention differs from this in attaching the plates or castings directly to the ends of the slats, and thus dispensing with the hanging supports, whereby the construction is cheapened, the blinds more easily operated, and the parts less liable to get out of repair.

60 What I claim as my invention, and desire to secure by Letters Patent, is—

1. A hanger for window-blinds, consisting of the plate A, bent at right angles, so as to be applied directly to the end of the top slat, 65 E, and having the slotted triangular end, B C, in combination with the support D, placed inside of the window-frame, substantially as shown.

70 2. The combination of the plate A, having a slot, B, and triangular end C, and adapted to be fastened directly to the end of the slat E and project beyond its side, with a support, D, secured to the inside of the frame, substantially as set forth.

CHARLES M. YOUNG.
